Letters Patent No. 1351. Dated Decr. 4th 1860.

The schedule referred to in these Letters Patent and making part of the same.

To all whom it may concern:

Be it known that I, Charles T. Meyer, of the City of Boston, County of Suffolk, State of Massachusetts, have invented or produced a new original and ornamental design or pattern for Floor Cloths, Carpets and other fabrics; and I do hereby declare that the accompanying pattern or drawing, marked and designated as Design No. 1, represents said design and is sufficient without further aid to enable any person skilled in the art, to which it appertains, to repeat it for practical use. The colors and the arrangement of them may in the use of this design be the same as shown in said pattern, or varied to suit the view or fancy of the user or manufacturer of the article ornamented by said design.

What I claim as my invention or production and desire to secure by Letters Patent, is the ornamental design represented in the accompanying pattern.
